W. MILLARD.

APPARATUS FOR MOISTENING AIR.

APPLICATION FILED JULY 28, 1917.

1,322,597.

Patented Nov. 25, 1919.

UNITED STATES PATENT OFFICE.

WILLIAM MILLARD, OF NEW YORK, N. Y., ASSIGNOR TO CARBON DESTROYER CORPORATION, OF NEW YORK, N. Y., A CORPORATION OF NEW YORK.

APPARATUS FOR MOISTENING AIR.

1,322,597.

Specification of Letters Patent. Patented Nov. 25, 1919.

Application filed July 28, 1917. Serial No. 183,323.

To all whom it may concern:

Be it known that I, WILLIAM MILLARD, a subject of the King of Great Britain, residing at the borough of Manhattan, city, 5 county, and State of New York, have invented certain new and useful Improvements in Apparatus for Moistening Air, of which the following is a specification, reference being had to the accompanying 10 drawings.

This invention relates to improvements in apparatus for impregnating a gas with water vapor and particularly to apparatus by means of which air is made moist 15 and then is incorporated in a carbureted mixture that is burned in the working cylinder of a gas-engine, such as the gas-engine or motor of an automobile; and an object of this invention is to provide an apparatus 20 of the character described which will prove simple in construction, comparatively cheap in manufacture and efficient in operation and use. Another object of this invention is to provide an apparatus 25 of the kind just referred to by means of which the results obtained will be uniform in character. Other features of this invention will be referred to hereinafter.

In the drawings illustrating the principle 30 of this invention and the best mode now known to me of applying that principle, Figure 1 is a central vertical section through the tank or reservoir of my air-moistener; Fig. 2 is a fragmentary section illustrating 35 a modified form of the tank or reservoir; Fig. 3 is a fragmentary section of a second modified form of the tank or reservoir; and Fig. 4 is a fragmentary elevation showing 40 a gas-engine cylinder and its mixture-moistening apparatus.

The body *b* of the tank or reservoir *a* is formed of a transparent glass cylinder that serves as a gage-glass and the lower end of which rests on a rubber gasket *c* held in the cup-shaped metal bottom *d* of the reservoir *a*. The metal cover or top *e* of the latter is likewise cup-shaped and receives the upper end of the glass body *b*, between which upper end and the top *e*, 45 there is interposed another rubber gasket *c'*. Through holes *f*, *g*, formed in the bottom *d* and the top *e*, respectively, of the reservoir *a*, there passes a tube *h*, the upper outer end *h'* of which is threaded exteriorly and the lower outer end of which is

formed with a head *h''*, between which and the bottom *d*, there is interposed a washer *i*. The gasket *c* and the washer *i* serve as sealing devices and prevent the water *j* from leaking out of the tank *a* through the bottom thereof. To the upper outer end *h'* of the tube *h*, there is screwed a mouthpiece *k*, between which and the top *e* of the reservoir *a*, there is interposed a washer *i'*. Should the reservoir *a* be inverted, the washer *i'*, and the gasket *c'* would prevent the water *j* from leaking out of the reservoir *a* through the perforated cup-shaped top *e*. Surrounding the centrally-disposed tube *h* and resting on the bottom *d* of the reservoir *a*, there is an inverted cup-shaped (or dished) member *m* the cylindrical wall *m'* of which is formed with holes *m''* and the top *m''* of which is formed with a central hole *m''* through 75 which passes the tube *h*. This member *m* constitutes what may be termed a false bottom; and, between the top *m''* of the latter and the bottom *d* of the reservoir *a*, the tube *h* is formed with holes *h''* for the passage of air drawn inwardly through the mouthpiece *k* and the tube *h*. Into an opening *e'* formed in the top *e* of the reservoir *a*, there is screwed one end of a pipe *n* the other end of which is connected with 80 the intake manifold *o* of the gas-engine cylinder *p* (Fig. 4). The pipe *n* is formed with a coil *n'* intermediate its ends and, through this pipe *n* and the manifold *o*, the engine-cylinder *p* is brought into communication with the reservoir *a*. As is common in gas-engines constructed for use in automobiles, the lower end of the manifold *o* 85 communicates with the carburetor *q*. When the piston *r* moves downward on its sucking stroke, an explosive mixture is drawn through the manifold *o* from the carburetor *q* into the cylinder *p*. At the same time, the air is drawn from the outside through the mouthpiece *k*, tube *h*, holes *h''* therein and holes *m''* in the false bottom *m*, the water *j* in the reservoir *a*, and the pipe *n*, into the manifold *o*, wherein it becomes mixed with the explosive carbureted mixture flowing therethrough from the carburetor *q*. By passing the air through the water *j* in the reservoir *a*, the air is moistened and, in turn, moistens the carburetor mixture with which it mingles and which flows into the cylinder *p*. By thus moisten- 90 95 100 105 110

ing the explosive mixture, the tendency of a deposit of carbon to form on the inside of the cylinder p is counteracted and so-called "carbon" troubles are in a great 5 measure avoided. It is universally recognized that so-called "engine" troubles are much less likely to arise in damp weather and in the cool of the evening than during the heat of a dry day. By the use of the 10 apparatus hereinbefore described, the atmospheric conditions existing on a wet day are, to a great extent, simulated; and the engine will be found to work smoothly even in dry weather, when the engine is equipped 15 with the hereinbefore-described apparatus. Should the quantity of water drawn over with the air through the pipe n be excessive, the surplus water will tend to separate from the air in passing through the 20 coil n' .

In the structure illustrated in Fig. 2, the false bottom m of Fig. 1 is replaced by a perforated drumlike receptacle s having both a bottom s' and a top s'' and being 25 raised slightly above the bottom d of the reservoir a .

In the apparatus shown in Fig. 3, the tube h^* is provided with perforated lateral extensions t formed with holes t' through 30 which the air passes from the tube h^* into the water j and thence to the pipe n .

The holes h^* in the lower or outlet end of the tube h are preferably very small holes, commonly called pinholes, and the same is 35 true of the holes m'' formed in the false bottom m . The air-passage n'' formed in the pipe n is likewise of small diameter preferably. The false bottom m , the drum s and the perforated lateral extensions t are 40 not essential and may be dispensed with, if so desired. Instead of water j , any suitable solution may be used. The water or solution may be held absorbed by any suitable absorbent material, such as a sponge, layers 45 of felt, a mass of cotton waste or the like.

The washer z' prevents air from leaking into the air-space b' above the water j ; and the gasket c' keeps the joints b'' between the body-portion b and cover or top e 50 practically air-tight. The washer z' and gasket c' are hence sealing devices. The parts of the reservoir a are held firmly together by the tube h and the mouthpiece k , which serve in this connection as a bolt and 55 a nut, respectively. The reservoir a is a knockdown structure; for, by unscrewing the mouthpiece k from the upper end of the tube h , the body-portion b , bottom d , cover e and tube h may be readily separated from 60 one another for the purpose of cleaning, renewal of worn parts or the making of other repairs. In order to replenish the supply of water (or solution) in the container a , the engine p is started and water is poured 65 into the container a through the mouthpiece

k . It will be found that the suction produced by the cylinder p causes the reservoir a to fill rapidly.

I am aware that apparatus have heretofore been devised for forcing air through 70 water for the purpose of purifying the latter; and an example of such an apparatus is disclosed by United States Patent No. 240813 granted May 3, 1881, to Sidney E. Collins. But the result sought to be attained 75 by the apparatus patented by Collins is entirely foreign to the object of the present invention, which consists in the combinations of parts hereinafter claimed.

I claim:

1. An apparatus for moistening air; including a closed reservoir having a body portion and a removable bottom and a removable cover therefor, sealing devices between said body portion and said bottom 80 and cover, means for pressing said body portion, bottom, cover and sealing devices together; said means being of conduit form and extended through apertures in the bottom and cover and open at its upper end and 85 in communication adjacent to its lower end with the interior of the reservoir and having a packed enlargement below the bottom and also having above the cover a packed enlargement of cup-form in communication 90 with and extending above said open upper end, one of said enlargements being removable, and a pipe for connecting said reservoir with the gas-engine cylinder.

2. An apparatus for moistening air; including a closed reservoir having a body portion and a removable bottom and a removable cover therefor, sealing devices between said body portion and said bottom and cover, a tube extending upwardly through 100 apertures in the bottom and cover and having a head below the bottom and a threaded portion above the cover and open at its upper end and apertured for communication with the lower portion of the interior of the 105 reservoir, a washer between the head and bottom, a cup threaded on the upper end of the tube and communicating with and extending above said end to serve as a funnel, and a washer interposed between the cup 110 and cover, and a pipe for connecting said reservoir with the gas-engine cylinder.

3. An apparatus for moistening air, including a reservoir comprising a body-portion, a bottom, a cover, an air-inlet tube detachably attached to and securing the bottom in place and having apertures in communication with the lower port of the reservoir, whereby air may be introduced into liquid in the reservoir below the liquid surface, and also having an upper open end, and a mouth piece detachably secured on the upper end of the tube, above the cover, with the upper open end of the tube flush with the lower wall of the mouth piece whereby 125 130

the mouth piece is enabled to act as a funnel in pouring liquid down the tube; the said body-portion being readily separable from said bottom and cover when said mouth piece is removed from said tube, and a pipe for connecting said reservoir with the gas-engine cylinder.

4. An apparatus of the character described for moistening air, including a closed reservoir one end of which is freely removable therefrom; an air inlet tube one end of which communicates with the outer air and the lower portion of which communicates with the lower portion of the interior of the reservoir; a mouthpiece which screws onto said end of the tube and locks the removable end of said reservoir in place and has its lower wall flush with the upper open end of the tube whereby said mouth piece may act as a funnel in pouring liquid down the tube; and a pipe for connecting said reservoir with the gas-engine cylinder.

5. An apparatus of the character described for moistening air including a closed reservoir having a body-portion and a cover therefor; a sealing device between said body portion and cover; means for pressing said body-portion, cover and sealing device together; said means being of conduit form and open at its upper end and in communication with the atmosphere and the lower portion of the interior of the reservoir; and a pipe for connecting said reservoir with the gas-engine cylinder.

6. In an apparatus of the character described, a reservoir including a body-portion, a bottom and a cover, said reservoir being adapted to hold water and said bottom and cover being each formed with a hole; an air inlet tube that passes through said holes and has an enlargement against the underside of the bottom; and a mouth-piece that is

screwed onto the end of said tube above the cover and serves as a nut to hold the said parts of said reservoir together, said tube being open at its upper end and in communication with the lower portion of the interior of the reservoir.

7. In an apparatus of the character described, a reservoir including a body-portion, end members that close the same and sealing devices for maintaining fluid-tight the joints between said body-portion and end members, said reservoir being adapted to hold liquid; an air-inlet tube that is mounted in said reservoir and which communicates at one end with the outer air and the other end of which communicates with the liquid-filled space in said reservoir; and means co-acting with the air-inlet tube and disposed against the outer sides of the end members for pressing said end members, sealing devices and body-portion together to make said joints fluid-tight. 65

8. In an apparatus of the character described, a knockdown liquid-containing reservoir including a body-portion and end members that close the same and are readily separable therefrom; an air-inlet tube that is mounted in said reservoir and which communicates at one end with the outer air and the other end of which communicates with the liquid-filled space in said reservoir; and means co-acting with the air-inlet tube and disposed against the outer sides of the end members for locking said body-portion and end members together to form a container. 70

Signed at the borough of Manhattan, city, county, and State of New York, this twenty- 80 seventh day of July, 1917, in the presence of the two undersigned witnesses.

WILLIAM MILLARD.
